Primary Examiner — Barbara Fox*Assistant Examiner* — Mehri F Bajoul*(74) Attorney, Agent, or Firm* — Downs Rachlin Martin PLLC**CLAIM**

The ornamental design for a soccer training ball, as shown and described.

DESCRIPTION

FIG. 1 is a perspective view of a soccer training ball showing my new design;

FIG. 2 is a front view thereof;

FIG. 3 is a rear view thereof;

FIG. 4 is a side view thereof;

FIG. 5 is a second side view thereof;

FIG. 6 is a top view thereof; and,

FIG. 7 is a bottom view thereof.

The broken lines shown in the drawings depict portions of the soccer training ball that form no part of the claimed design.
